UNITED STATES PATENT OFFICE.

NATHAN BERMAN, OF PHILADELPHIA, PENNSYLVANIA, ASSIGNOR TO LOTTIE T. BERMAN, OF PHILADELPHIA, PENNSYLVANIA.

TRACK-LINER.

1,273,569.

Specification of Letters Patent.

Patented July 23, 1918.

Application filed January 13, 1917. Serial No. 142,224.

To all whom it may concern:

Be it known that I, NATHAN BERMAN, a citizen of the United States, residing at Philadelphia, in the county of Philadelphia and State of Pennsylvania, have invented 5 certain new and useful Improvements in Track-Liners, of which the following is a specification.

My invention consists of an improved 10 track liner, and is particularly adapted for bodily shifting railroad tracks.

One object of my invention is to provide a device of simple construction by the use of which railroad tracks can be easily and 15 quickly shifted and re-aligned.

Another object is to so construct my invention that it may be easily handled and carried by a workman and will be strong and durable.

20 These objects, and other advantageous ends which will be described hereinafter, I attain in the following manner, reference being had to the accompanying drawings in which—

25 Figure 1 is a fragmentary elevation showing two positions of a shifting bar which forms a part of my invention, one of the positions being shown in full lines prior to the movement of a track, the other position 30 being shown in dot-and-dash lines showing the effect of movement of the bar on the track.

Fig. 2 is a top plan view, on a smaller scale than shown in Fig. 1, showing in dot-and-dash lines the shifted position of the track.

Fig. 3 is a section on the line 3—3 of Fig. 2 on a slightly enlarged scale.

Fig. 4 is a fragmentary perspective view 40 of a railroad track showing the position occupied by my invention when used to shift the track, and

Fig. 5 is a perspective view of the lower 45 end of the shifting bar which forms a part of my invention.

Referring to the drawings, the track of which only one rail 1 is illustrated, includes ties 2 which are spaced apart in the usual manner. This track, as illustrated, rests 50 upon a road bed 3 which may consist of crushed stones or other suitable material.

My invention consists of a flat plate 4 having brackets 5 secured thereto by rivets 6 or other suitable means. These brackets are 55 spaced apart and have upwardly projecting

ears 7 through which extends a pivot pin 8. This pin is preferably forced through both of the ears 7 so as to be securely held therein during the operation of the device and projects through an elongated slot 9 formed 60 within my improved shifting bar 10.

The lower end 11 of the bar 10 has a curved edge surface 12 designed to rock upon the upper surface of the plate 4 as will be hereinafter more fully described. 65 The curved edge surface 12, adjacent the extreme lower end 13 of the bar 10 blends with a substantially flat edge surface 14. The edge surface opposite the edge surface 12 is also curved as shown at 15, the slot 70 9 being formed in the material between these two curved edge surfaces 12 and 15.

The bar 10 at its upper portion is designed to receive a handle 16 which is preferably made tubular so as to embrace the upper 75 end of the bar and to increase the leverage. The edge portion of the bar between the curved part 15 and the extreme end 13, is preferably made substantially flat as at 17 for a purpose hereinafter described. 80

The pivot pin 8 is of smaller diameter than the width of the slot 9 in the bar 10.

In the use of my invention, the plate 4 is inserted between the ties 2 and rests on the upper surface of the roadbed. The entire 85 device, including the plate 4 and the lower end of the bar 10, is slid under the base of the rail 1 as clearly shown in full line positions in Fig. 1, and until the curved edge surface 15 of the bar 10 engages the edge 18 90 of said rail 1. The bar 10 is then rocked through the medium of the handle 16 which raises the portion 17 into contact with the edge 19 of said rail 1.

A continued rocking movement of the bar 95 10 raises the rail 1 and with it the ties 2, and simultaneously shifts the track laterally, for example, into the dot-and-dash line position shown in Figs. 1 and 2.

When the handle 16 is again raised, the 100 lifted rails and ties will fall again into contact with the roadbed but in a shifted position, it being noted that the flat surface 17 permits the rail to readily slide or fall downwardly under the control of the bar 10. 105

By forming the slot 9 at the angle illustrated and making the pin of a diameter less than the width of said slot, the lifting strain is removed from the pin, the pin merely acting to hold the shifting bar in its proper 110

position relatively to the plate 4. Also, by having the edge 14 substantially flat, the end 13 firmly rests upon the plate 4 and the construction is such that comparatively little 5 room is required between the under surface of the rail and the top of the roadbed to permit the proper positioning of my invention. This feature is of practical importance since there is often very little room 10 between the upper surface of the roadbed and the bottom surface of the base of the rails.

By the use of my invention, tracks may be bodily moved or shifted either to re-align 15 them or during their installation.

While I have described my invention as taking a particular form, it will be understood that the various parts of my invention may be changed without departing 20 from the spirit thereof, and hence I do not limit myself to the precise construction set forth, but consider that I am at liberty to make such changes and alterations as fairly come within the scope of the appended 25 claims.

Having thus described my invention, what I claim as new and desire to secure by Letters Patent is:

1. A track liner comprising a plate having 30 a plane bottom surface free of projections designed to be inserted under a rail, a shifting bar mounted to rock on the plate, said bar having a curved end portion designed to be projected under the base of the rail from 35 one side thereof and when rocked to engage said rail at the opposite side thereof to raise and laterally pull the rail into a shifted position, said end portion having a substantially flat lower edge surface adjacent its extreme 40 end and designed to engage the upper surface of said plate, said end portion also having a curved edge blending with said flat edge and designed to rock upon the upper surface of said plate, said portion of the bar having a rail-engaging edge surface, the 45 portion of said latter surface adjacent the extreme lower end being substantially flat and blending with a curved edge surface, said latter curved edge surface being opposite the curved surface which engages said 50 plate during the rocking movement of the bar, said bar having an elongated slot extending between said curved edge surfaces, brackets on said plate and having vertical 55 ears, and a pin supported by said vertical ears of said brackets and extending through said slot, said slot extending in such direction that when the shifting bar is in its raised position the slot will extend at an angle slanting in one direction and when the shifting bar is rocked into its lower position said slot will extend at a slant in the opposite direction whereby the rocking movement of said shifting bar will cause it to move longitudinally in one direction and 60 then during the final rocking movement to move longitudinally in an opposite direction, substantially as described.

slant in the opposite direction whereby the 55 rocking movement of said shifting bar will cause it to move longitudinally in one direction and then during the final rocking movement to move longitudinally in an opposite direction, substantially as described.

2. A track liner comprising a plate having 60 a plane bottom surface free of projections designed to be inserted under a rail, a shifting bar mounted to rock on the plate, said bar having an end portion designed to extend under the base of the rail from one side 65 thereof and when rocked to engage said rail at the opposite side thereof to laterally shift it, said end portion having a substantially flat lower edge surface adjacent its extreme 70 end and designed to engage the upper surface of said plate, said end portion also having a curved edge blending with said flat edge and designed to rock upon the upper surface of said plate, said portion of the bar having a rail-engaging edge surface, the 75 portion of said latter surface adjacent the extreme lower end being substantially flat and blending with a curved edge surface, said latter curved edge surface being opposite the curved surface which engages said 80 plate during the rocking movement of the bar, said bar having an elongated slot extending between said curved edge surfaces, brackets on said plate and having vertical 85 ears, and a pin supported by said vertical ears of said brackets and extending through said slot, said slot extending in such direction that when the shifting bar is in its raised position the slot will extend at an angle slanting in one direction and when the shifting bar is rocked into its lower position said slot will extend at a slant in the opposite direction whereby the rocking 90 movement of said shifting bar will cause it to move longitudinally in one direction and then during the final rocking movement to move longitudinally in an opposite direction, substantially as described.

In testimony whereof I have signed my name to this specification in the presence of 100 two subscribing witnesses:

NATHAN BERMAN.
